UNITED STATES PATENT OFFICE.

NIELS K. ANDERSEN, OF WILKINSBURG, PENNSYLVANIA, ASSIGNOR TO WESTINGHOUSE ELECTRIC & MANUFACTURING COMPANY, A CORPORATION OF PENNSYLVANIA.

ALTERNATING-CURRENT ELECTROMAGNET.

Application filed October 20, 1927. Serial No. 227,401.

This invention relates to electromagnets and particularly to electromagnets of the alternating-current type.

An object of the invention is to provide an alternating-current electromagnet in which the magnetic attraction between the armature and the stator shall not fall below a predetermined value.

A further object of the invention is to provide an alternating-current electromagnet that shall be adapted for energization from alternating-current circuits independently of the frequency.

A still further object of the invention is to provide an alternating-current electromagnet that shall be simple in construction and easily manufactured and in which there shall be substantially no vibration between the armature and the stator.

For a fuller understanding of the invention, reference may be had to the following description, taken in conjunction with the accompanying drawing, in which:

Figure 1 is a front view, in elevation, of an alternating-current electromagnet embodying the invention.

Fig. 2 is a view, in side elevation, of the same device.

Fig. 3 is a view, in section, taken on line III—III of Fig. 1.

Fig. 4 is a view, in side elevation, of a sheet-metal punching or lamination embodied in the armature of the electromagnet shown in Figs. 1 and 2.

Fig. 5 is a view, in side elevation, of a sheet-metal punching or lamination embodied in the stator or the core of the electromagnet of the device shown in Figs. 1 and 2.

Fig. 6 is an edge view illustrating the thickness of the laminations shown in Figs. 4 and 5, and

Fig. 7 is a series of curves illustrating the variation in magnetic attraction between the armature and the stator or the core of the electromagnet shown in Figs. 1 and 2.

In Figs. 1 and 2 of the drawings, a base 1 of cast-metal or other suitable material is illustrated, and a core 2 of substantially E-shape is secured to it. The core comprises a plurality of relatively thin laminations 3 of magnetic material of substantially E-shape (see Fig. 5). The bottom edges of the laminations 3 are clamped between angle irons 4 and 5 by means of bolts 6. Each of the legs

of the laminations 3 are clamped together by bolts which extend through openings provided therein.

The outer legs of the laminations 3 are provided with alined notches 7 which form a rectangular slot in the end of each leg of the core for receiving a conductor 8. In this construction, the conductor 8 is insulated from the core by tubular members 9 of insulating material. On one side of the core, the conductor 8 is bent downwardly against the base 1 and is secured thereto by clips 10.

The ends of the conductor 8 are provided with terminal clips 11. In order to secure the ends of the conductor 8 to the base 1, stud bolts 12 are provided to make threaded engagement with the base. As shown, the stud bolts are provided with lock nuts 13 for locking them in place. The stud bolts 12 project through tubular insulating members 14 mounted in openings in the terminal clips 11 (see Fig. 3). The clips 11 are insulated from the base 1 by insulating washers 15.

In order to provide a closed circuit, the ends of the conductor 8 may be connected by a resistor 16, having a resistance of a predetermined value. The resistor may be secured, at its ends, in intimate contact with the terminal clips by means of nuts and lock washers 17, the latter being of insulating material and disposed between the resistor and the lock washers for insulating the conductor from the base. The conductor 8 and the resistor member 16, being connected together, may be utilized as a shading coil, for a purpose to be hereinafter set forth.

In order that lines of alternating magnetic force may be caused to permeate the legs of the E-shaped core 2, an electromagnet coil 18 is provided to encircle the middle leg of the core 2. The coil is provided with a clamping plate 19 and bolts 20 for securing it to the base 1.

Since the coil 18 is disposed on the middle leg of the core 2, magnetic flux is caused to flow through the outer legs of the core in the same direction and to return through the middle leg in response to electric current flowing through the coil. If the coil 18 is energized from a source of alternating power, a current will be induced in the shading coil. The current flowing in the shading coil will produce a magnetic flux in the core that lags substantially 90 degrees behind the flux pro-

duced by the coil 18. The purpose of establishing two magnetic fluxes in the core, that are displaced in phase from each other, will be hereinafter set forth in detail.

- 5 The core 2 is provided with an armature 21 of substantially E-shape that comprises a plurality of laminations 22 (see Fig. 4) secured together by bolts or other suitable means. The armature is pivotally mounted 10 at 23 on a supporting arm 24, which, in turn, is pivotally secured at 25 to a bracket 26, the bracket 26 being secured to the base 1.

The middle legs of the laminations constituting the armature 21 and the core 2 are 15 cut on a bias and of such length that an air gap 27 is provided therebetween when the outer legs of the core and the armature are in engagement (see Fig. 2). If an air gap be provided, as shown, the tendency of the armature 20 to stick to the core 2 when the coil 18 is deenergized is obviated.

When the coil 18 is energized, a current is induced in the shading coil comprising the conductor 8 and the resistor 16. Thus, two 25 magnetic fluxes are developed in the core and the armature, one by the coil 18 and the other by the shading coil.

The magnetic attraction or pull resulting 30 between the core and the armature, caused by the lines of magnetic force produced by the coil 18, may be represented by a curve 29 of Fig. 7. This curve illustrates that the pull or magnetic attraction varies between a maximum value and zero.

35 The magnetic attraction or pull between the armature and the core, resulting from the lines of magnetic force developed by current flowing in the shading coil, may be represented by the curve 30, which indicates also 40 that the magnetic pull varies between a maximum value and zero.

Since the current induced in the shading coil lags behind the current flowing in the coil 18, the fluxes produced by the respective 45 coils will be displaced in phase by substantially 90 electrical degrees. Since the fluxes acting upon the armature combine to produce a resultant flux, the magnetic attraction or pull between the armature and the core may 50 be represented by a curve 31 which is a summation of the curves 29 and 30. Therefore, it will be seen that the minimum magnetic 55 attraction between the armature and the core never falls to zero and, therefore, the armature is held firmly against the core 2. Under such operating conditions, vibration and chattering of the armature are substantially eliminated.

The amplitude of the curve 30, which represents the magnetic attraction between the core and the armature produced by the current flowing in the shading coil, may be controlled by utilizing resistors of different ohmic values.

60 Since the resistor 16 may be removed, and

the resistance of the shading coil circuit controlled by replacing the resistor 16 with another of the proper resistance, the coil 18 of the electromagnet may be utilized on substantially any electrical circuits of commercial frequency, because the resultant curve 31 may be controlled by governing the amplitude of the curve 30 which, as hereinbefore stated, is determined by the currents flowing in the coil 18 and the shading coil. 70 75

The electromagnet, illustrated in the drawings, may be assembled as a compact unitary structure and mounted on circuit breaker panels, or wherever needed, for actuating circuit interrupters or other devices. Since 80 the magnet is applicable to circuits of substantially all commercial frequencies, it may be described as a universal electromagnet.

Since various modifications in the device embodying the invention may be made without departing from the spirit and scope thereof, I desire that only such limitations shall be placed thereon as are imposed by the prior art and the appended claims.

I claim as my invention:

1. In an electromagnet, in combination, a plural-leg magnet core of substantially E-shape, an induction coil disposed on the middle leg for causing lines of magnetic force to permeate the legs of said core, a shading coil wound upon the outer legs and inductively coupled to said induction coil, a resistor for short-circuiting said shading coil to cause lines of magnetic force to permeate said core responsive to current flowing in said induction coil, and means for insulating said resistor and shading coil from the core. 90 95 100

2. In an electromagnet, in combination, a magnet core, an induction coil for causing lines of magnetic force to flow in a plurality of paths in the core, an armature for said core, a shading coil inductively coupled with, and responsive to, current flowing in the main coil for causing lines of magnetic force, displaced in phase from the lines induced by the induction coil, to flow in said core, and a removable resistor for short-circuiting said shading coil, whereby the magnetic pull between the armature and the core may be prevented from falling below a predetermined 110 115 value while the main coil is energized.

3. In an electromagnet, in combination, a magnet core, a main coil for causing lines of magnetic force to flow in a plurality of paths in the core, an armature for said core, a shading coil inductively coupled with, and responsive to, current flowing in the main coil for causing lines of magnetic force to flow in said core that are displaced in phase from the lines of magnetic force produced by the induction coil, and a removable resistor for short-circuiting said shading coil, whereby the magnetic pull between the armature and the core may be prevented from falling below a predetermined 120 125 130 value while the main coil is en-

ergized, said core, coils and armature being assembled as a unitary structure.

4. In an electromagnet, the combination with a base, a core of substantially E-shape, a 5 coil disposed on the middle leg of the core for causing lines of magnetic force to permeate the core, of means for producing a second magnetic flux out of phase with the first magnetic flux comprising a conductor looped 10 around said coil and disposed in the outer legs of said core, means for securing the ends of said conductor to said base, means for insulating the conductor from the core and the base, and a removable resistor member connected 15 to the ends of the conductor.

5. In an electromagnet, a stator of substantially E-shape, an induction coil disposed on a middle leg thereof, an armature of substantially E-shape for cooperating with said 20 stator, a conductor disposed upon the outer legs of the stator, means for securing the ends of the conductor to the stator, means for insulating the conductor from the stator, and a removable resistor connected to the ends of 25 the conductor whereby a current is induced in said coil responsive to current flowing in the induction coil for producing lines of magnetic force displaced in phase relation from

the lines of magnetic force caused by the induction coil. 30

6. In an alternating-current electromagnet, the combination with a stator of E-shape, an armature of E-shape, and an induction coil disposed on the middle leg of the stator for causing lines of magnetic force to permeate 35 the stator, of a conductor disposed on the outer legs of said stator, means for insulating said conductor from the core, means for securing the terminals of said conductor to said stator and a removable resistor connected to 40 the terminals of said conductor.

7. In an electromagnet, in combination, a plural-leg magnet core, an induction coil disposed on one leg of said core for causing lines of force to permeate the legs of said core, a 45 shading coil wound upon the other legs of said core and inductively coupled to said induction coil to cause lines of magnetic force to permeate said core responsive to current flowing in said induction coil, and means for varying 50 the resistance of said shading coil.

In testimony whereof, I have hereunto subscribed my name this 7th day of October, 1927.

NIELS K. ANDERSEN.
